HARRY GRUMBACH, OF NEW YORK, N. Y., ASSIGNOR TO SIMON ASCHER AND COMPANY, INC., OF NEW YORK, N. Y., A CORPORATION OF NEW YORK

KNITTED HELMET

Application filed May 30, 1930. Serial No. 457,639.

This invention pertains generally to knitted garments and particularly to knitted garments adapted for use as headwear.

The invention will be described in connection with a knitted helmet. However it is understood that it may be applied in many other ways.

Knitted materials when used for helmets, caps and the like have a tendency to become stretched out of shape and to become baggy in places, particularly along the top from the front to the rear. The result is that the article becomes unsightly in appearance and is ill fitting.

According to this invention the rows of stitching, that is, the courses are arranged so as to eliminate all undue stretching and bagging of the material and to cause the helmet, cap or similar article to cleave closely to the

head at all times. This result is accomplished by arranging the rows of stitches making up the top portion of the cap in an inverted V at both the front and the rear and increasing the angle of the V progressively towards the top centre, until the former inverted V's are eventually merged in a substantially straight line. When constructed in this manner the tension exerted on the top portions by the side portions draws the top portion tightly down onto the head over its entire length from front to rear. The side portions may be formed in any known manner, so as to grip the head to remain in position or may be provided with flaps, which unite under the chin so as to form a helmet.

To add to the natural tendency of the article to form itself to the head, the top portions may be made arcuate in cross-section; the arc being in concave relationship with the top of the cap.

Referring to the drawings in which like reference characters are appended to like parts throughout the various views:

Figure 1 is a perspective view of a helmet.

Figure 2 is a perspective view of the helmet illustrated in Figure 1 but from a different angle.

Figure 3 is a perspective view of the helmet illustrated in Figure 1, showing a side and the rear thereof.

Referring to the drawings, at 1 is shown a helmet, comprising top portions 2 and 3 secured together at 4a and side portions 4 and 5. Side portion 4 is secured to the top portion 3, as illustrated at 6, and side portion 5 is secured to top portion 2, as illustrated at 7.

Side portions 4 and 5 are shown provided with extensions 8 and 9, which overlap at 10 and may be secured with a snap 11. It is, of course, understood that any other form of side portion may be employed, but preferably one that is adapted to exert at least a slight tension on the top portions, when the cap is in position on the head. The purpose of this tension will be set forth hereinafter.

The selvage at the front and rear openings may be finished in any desired manner, as illustrated at 12 and 13.

The top portions 2 and 3 have their rows of stitching, that is the courses, arranged at both the front and rear so as to slope towards the top centre of the cap. This arrangement results in a plurality of inverted V's formed by the rows of stitching. The inverted V's at the front of the cap are clearly seen at 14, in Figures 1 and 2. In Figure 3 the V's at 14 are shown in upright position. The inverted V's at the rear of the helmet are clearly seen at 15 in Figure 3. The arrangement is such that at some point intermediate the front and the rear of the top portion and adjacent the top centre, the inverted V's 14 and 15 merge together from opposite sides into a more or less straight line, as illustrated at 16.

The side portions 4 and 5 may have the rows of stitching running in any desired direction. However, I find that by arranging the rows of stitching 19 of the side portions 4 and 5, so that they will be substantially horizontal when the helmet is in position on the head, that a substantially even tension is exerted upon the longitudinal edges of the top portions 2 and 3.

The top portions 2 and 3 are shown joined together by seam 4a. After the seam is made I may draw the portions 2 and 3 down around the seam by any means, such as stitching from underneath. Top portion 3 may be joined to side portion 4 and top portion 2

- may be joined to side portion 5 in the same manner. The result is that the top portions 2 and 3 have an inwardly sloping arcuate cross-section, as illustrated at 17. 5
- 5 The knitting is not limited to any particular type of stitch. But the type of knitting illustrated in the drawing has wales shown at 18 on the inside of the helmet running at right angles to courses on the outside. 10
- 10 When the helmet illustrated is placed upon the head and the side portions 4 and 5 drawn downward, the tension on the rows of stitches 14 and 15 is such, as to draw the top seam 4a, as well as the top portions 2 and 3 tightly down onto the head. The tension on the seam 4a and portions 2 and 3 is not only in a direction toward the front and rear of the head, but also from the sides to the center. Any 15 tendency towards bunching is thus effectively overcome. When the portions 2 and 3 are made arcuate, as above described, a lesser sidewise tension on these portions is required to cause them to fit snugly to the head. 20
- 20 While I have described the invention in connection with a helmet having two top portions and two side portions, it is obvious that the entire helmet may be made in one piece, if desired, or any number of pieces. It is also obvious that the top portions 2 25 and 3 may be made of one piece, having adjacent sections, the rows of each section defining an angle with the rows of the other section in the manner as above set forth. 30
- 30 While the invention has been described in connection with courses, it is understood that wales may be substituted therefor without departing from the spirit of the invention. The term "rows of stitching" as used in the 35 claims is intended to mean courses and the term "rows of knitting" as used in the claims is intended to include rows made entirely 40 from courses or rows made entirely from wales. 45
- Having described my invention it is obvious that many modifications may be made in the same within the scope of the claims without departing from the spirit thereof. 50
- I claim:
1. A knitted head-piece, comprising adjacent top members having angularly related rows of knitting, said angularly related rows forming an inverted V with respect to the selvage at both the front and rear of the head-piece, the angle between said rows increasing from both the front and rear towards the central top portion and merging into each other, and side members attached to said top portion, said side members adapted to exert a substantially even tension on the longitudinal edges of said top portion when the head-piece is in place on the head. 55
3. A knitted head-piece comprising adjacent top members having angularly related rows of stitching, said angularly related rows forming an inverted V with respect to the selvage at both the front and the rear of the head-piece, the angle between said rows increasing from both the front and the rear towards the central top portion and merging into each other, and side members attached to said top members, said side members adapted to exert a tension on the longitudinal edges of said top members when the head-piece is in place, said top members adapted to normally assume a concave cross-section between their longitudinal seams. 60
- In testimony whereof, I have signed my name to this specification this 24th day of May, 1930. 65
